UNITED STATES PATENT OFFICE.

NOBLE LE R. LYONS, OF AKRON, IOWA.

BROOM AND DUST-PAN HANGER.

No. 873,762.

Specification of Letters Patent.

Patented Dec. 17, 1907.

Application filed December 17, 1906. Serial No. 348,171.

To all whom it may concern:

Be it known that I, NOBLE LE R. LYONS, a citizen of the United States, residing at Akron, in the county of Plymouth and State of Iowa, have invented a new and useful Improvement in a Broom and Dust-Pan Hanger, of which the following is a specification.

This invention is a combined broom and dust pan holder, the object being to provide 10 a highly efficient combination device formed from a single piece of wire and adapted to be secured in the wall for the purpose of holding the broom in an upright position and also providing a convenient means for suspending 15 the dust pan, and with these objects in view the invention consists in the novel features of construction hereinafter fully described, and pointed out in the claims.

In the drawings forming a part of the 20 specification:—Figure 1 is a perspective view showing the practical application of my improved construction of dust pan and broom holder. Fig. 2 is a top plan view of the device. Fig. 3 is a side elevation. Fig. 4 is a 25 top plan view showing the broom removed. Fig. 5 is a detail perspective view. Fig. 6 is a detail sectional view on the line 6—6 of Fig. 4.

In constructing a combination device in 30 accordance with my invention I employ a single piece of stout spring wire which at its center is coiled one or more times in the form of a circle as shown at A and after being so coiled, the members B, are extended 35 obliquely across each other as shown at C and each arm or member B is then coiled one or more times in the form of a circle as shown at D, and after being so coiled the wire is carried rearwardly as shown at E and one 40 strand thereof is continued in a horizontal line and threaded as indicated at F to provide a suitable shank which is adapted to be inserted in the wall or other rigid object to which the device is to be attached, while the 45 other member is carried downwardly and outwardly, and bent back upon itself and returned and wrapped as shown at G, and where the said member is bent back upon itself, after being carried downwardly and 50 outwardly, a hook H is provided which hook is intended to support the dust pan I, as most clearly shown in Fig. 1, the hook mem-

ber resting flat against the wall as most clearly shown in Figs. 1 and 3.

The members E are made slightly divergent as most clearly shown in Fig. 4 in order to more firmly grasp the handle K of the broom, as most clearly shown in Fig. 2. In order to insert the broom handle in the support, it is only necessary to force said handle against the coils D which coils immediately separate and the handle will then pass in between the members E but the cross members B will serve to limit the inward movement of the handle and at the same 60 time serve to impart the proper pressure upon the coils D and members E, said cross members B receiving their force from the central coil A.

In order to remove the broom handle it 70 will of course only be necessary to quickly withdraw the handle from the support and the said support then resumes its normal shape as shown at Fig. 4.

It will thus be seen that I provide an exceedingly cheap simple and efficient form of combination device capable of supporting both the broom and dust pan. It will of course be understood that any other article having a handle can be supported equally 80 as well as a broom.

Having thus fully described my invention, what I claim as new and desire to secure by Letters Patent, is:—

1. A device of the kind described formed 85 from a single piece of wire comprising a threaded shank, and a hook depending therefrom, a pair of grasping members terminating at their forward ends in coils, and a central coil arranged remote from the forward 90 end of the grasping members connected to each of said coils.

2. A device of the kind described formed 95 from a single piece of wire and comprising a central coil, cross arms extending from said central coil and terminating in coils at their forward ends, rearwardly extending grasping members, one of said members terminating in a shank and the other in a depending hook member as set forth.

NOBLE LE R. LYONS.
